Patented Nov. 1, 1898.

W. BORRMAN.
BALANCE PUMP.

(No Model.)

(Application filed Aug. 9, 1897.)

UNITED STATES PATENT OFFICE.

WILLIAM BORRMAN, OF NORFOLK, NEW YORK, ASSIGNOR TO FREDERICK C. AUSTIN, OF CHICAGO, ILLINOIS.

BALANCE-PUMP.

SPECIFICATION forming part of Letters Patent No. 613,233, dated November 1, 1898.

Application filed August 9, 1897. Serial No. 647,560. (No model.)

To all whom it may concern:

Be it known that I, WILLIAM BORRMAN, a citizen of the United States, residing at Norfolk, in the county of St. Lawrence, in the 5 State of New York, have invented a certain new and useful Improvement in Balance-Pumps, of which the following is a specification.

My invention relates to pumps adapted for 10 lifting water from a well or pool and for discharging the same at some suitable elevated point.

Prominent objects of my invention are to 15 reduce to a minimum the power required in operating the pump, to increase the pumping capacity, to reduce the strain and wear and tear upon the operating mechanism, and to accomplish such results in a simple, economical, and efficient manner.

20 In a pump characterized by my invention two columns of water are intermittently lifted and discharged by means of a couple of sets of coacting pumping members—that is to say, a couple of sets of pumping members whereof 25 those in each set coöperate with one another to lift one of the columns of water when the pump is in operation. In these two sets the members which simultaneously support the two columns of water during the operation of 30 the pump are interconnected, so as to place the weights of such columns continually in opposition to one another—that is to say, so that the downward pull on the part of either column will be always opposed by the downward pull on the part of the other. In this way 35 the two columns of water will tend to balance or support one another, and so when either one is elevated the weight actually lifted will not be the entire weight of such column, but 40 will be the weight of the same less the extent of opposition on the part of the other column.

The accompanying drawing is a view, partly in elevation and partly in section, of a pump embodying my invention.

45 In this arrangement a couple of vertically-disposed pumping-barrels A and A' are arranged in position above the well or pool from which the water is to be drawn, with their lower ends immersed therein. These barrels 50 A and A' are of substantially the same length,

(a portion of which is omitted from the drawing for convenience of illustration,) which length is such as to allow the elevation of the water to the predetermined elevated point. Said barrels are respectively provided near 55 their upper ends with suitable discharge nozzles or spouts a and a' and at points below the latter with suitable upwardly-opening pumping-valves a² and a³.

A couple of pumping-plungers B and B' are 60 arranged, respectively, within the barrels A and A' and above their pumping-valves a² and a³ and are respectively constructed with upwardly-opening pumping-valves b and b', which latter are adapted to coact, respectively, with one and the other of the barrel-valves a² and a³, so as to cause a pumping action in one or the other of the two barrels A and A' when one or the other of them is successively shifted in alternately reverse or 70 opposite directions relatively to one or the other of the barrel-valves. As a simple and desirable way for producing this relative shifting action between the coacting plungers and barrels the said barrels are arranged for 75 corresponding and simultaneous vertical reciprocation in simultaneously opposite directions, a simple and efficient arrangement being to suspend the barrels from and pivotally connect their upper ends to the opposite ends 80 of a vertically-swinging walking-beam C, which is pivotally supported at a point midway between its ends—as, for example, by a hanger D, attached to an upper cross-beam E. In this way the two columns of water are 85 successively and alternately lifted by the barrels an extent equal to the extent of reciprocation on the part of the latter and are alternately and successively supported by the plungers during the periods intervening between their periods of elevation, and therefore in either barrel simultaneously with the elevation of the other, so as to allow their upper portions to be alternately and successively discharged through the barrel discharge nozzles or spouts when the latter are alternately and successively lowered to an extent to come into position below their upper ends. It will thus be seen that while the two barrels form, respectively, with one and 90

95 100 A and A' are of substantially the same length,

the other of the two plungers with which they coact a couple of simultaneously-operating pairs of coacting pumping members such barrels also form, respectively, with one and 5 the other of the two plungers with which they do not coact a couple of alternately-operating pairs of simultaneously-supporting members. The barrels A and A' could be thus reciprocated by any suitable means, a 10 simple and convenient arrangement being to apply to one of them—as, for example, to the barrel A—the upper end of a reciprocating pitman F, which is operated by a crank G on a rotary shaft H. The bearings for the shaft 15 H are conveniently mounted on a lower cross-beam J, which is extended horizontally above the well or pool and is desirably provided with suitable guides for the barrels A and A', as indicated by dotted lines in the drawing. 20 The non-coacting plunger and barrel comprising each pair of the two alternately-operating pairs of simultaneously-supporting members are connected together in opposition—that is to say, they are so connected as 25 to place the weights of the two columns of water which they simultaneously sustain in opposition to one another, so that the one will tend to balance the other. This is clearly shown in the drawing, where, it will be observed, the column of water at the right is 30 practically supported or upheld by the plunger B', while the column at the left is practically supported or upheld by the barrel A by reason of its closed valve a^2 , and as the 35 said barrel A and plunger B' are respectively attached to opposite ends of the lever M' the two columns of water will thereby tend to counterbalance each other.

As an exceedingly simple and effective ar-

40 rangement the upper ends of the plunger-operating rods L and L' are respectively connected to the ends of a couple of horizontally-arranged levers M and M', which latter have their opposite ends in turn respectively connected to one and the other of the two barrels A and A' and are fulcrumed at points intermediate of their ends—as, for example, by being supported by a couple of hangers P and P', respectively, which are attached to 45 the upper cross-beam E. In this way the two columns of water are, in effect, simultaneously suspended from the opposite ends of one or the other of a couple of levers in alternation, and their weights therefore tend to 50 continually counterbalance one another.

55 The levers M and M' are of course vibrated or swung about their fulcrums by the reciprocation of the barrels A' and A, to which they are respectively connected, and so operate to reciprocate the plungers B and B' synchronously with their coacting barrels. In order, therefore, to still allow a relative shifting movement between the plunger and barrel comprising, respectively, one and the other 60 of the two pairs of coacting pumping members, the levers M and M' are respectively fulcrumed at points between their longitudi-

nal middles and their points of connection with the plunger-operating rods L and L', so that while the plungers will reciprocate synchronously and in the same direction with their respectively coacting barrels they reciprocate to an extent less than the extent of reciprocation on the part of the latter. The exact location of the points of fulcrum 70 of the levers M and M' could be anywhere between their longitudinal middles and their respective points of connection with the plunger-operating rods L and L'. It will be observed, however, that the nearer such fulcrums are situated to the longitudinal middles of the levers the nearer to a true counterbalance will the opposition of the two columns of water become, but at the same time the less will be the extent of relative shift on 80 the part of the coacting members comprising, respectively, one and the other of the two pumping sets and that on the other hand the nearer such fulcrums are situated to the points of connection of the plunger-operating rods the greater will be the extent of relative shift between such coacting pumping members, but at the same time the farther from a true counterbalance will the opposition of the weights of the two columns of water become. I therefore desirably locate the fulcrums for such levers at points substantially midway between the longitudinal middles thereof and the points of connection thereof with the plunger-operating rods, and thereby cause the opposition of the weights to one another to approach as nearly as possible to a true counterbalance without at the same time lessening to too great an extent the amount of relative shift between the coacting pumping members.

In order to permit the proper vibratory or swinging motion of the levers M and M', they are pivotally connected to the plunger-operating rods L and L', respectively, and also to 110 the hangers P and P', respectively, and have sliding connections with the barrels A' and A, respectively—such, for example, as the pins N and N' on the barrels and the slots m and m' in the levers.

115 The water discharged from the barrel-nozzles a and a' can be conveniently received by a suitable trough Q, supported by the lower cross-beam J by means of suitable legs R R, and can be conveyed from such trough for 120 use by means of a pipe S, attached to the side thereof.

What I claim as my invention is—

1. A pump comprising a couple of vertically-arranged valved pumping-barrels arranged 125 for simultaneous and corresponding vertical reciprocation in simultaneously opposite directions; means for thus reciprocating the barrels; a couple of valved pumping-plungers respectively confined within and coacting 130 with, the reciprocating pumping-barrels; and a couple of levers respectively connected at their opposite ends with a non-coacting barrel and plunger and fulcrumed at points be-

tween their longitudinal middles and their points of connection with the plungers, as set forth.

2. A pump comprising a couple of vertically-arranged and simultaneously-reciprocating pumping-barrels respectively provided with nozzles or spouts and upwardly-opening lift-valves; a pivotally-supported walking-beam C pivotally connected with the upper ends of the pumping-barrels; a crank and pitman for simultaneously reciprocating the barrels; a couple of plungers arranged respectively within the simultaneously-reciprocating pumping-barrels and respectively provided with upwardly-opening lift-valves; operating-rods pivotally connected with said plungers; and a couple of vertically-swinging levers having their opposite ends respectively slidably connected with one of the barrels, and pivotally connected with the plunger-operating rod of the other barrel, and pivotally supported at points between their ends and nearer to

their rod connections than to their barrel connections, substantially as described.

3. A pump comprising the pumping-barrels A and A' provided respectively with upwardly-opening lift-valves; the walking-beam C; means for reciprocating the said barrels simultaneously in opposite directions; a couple of plungers arranged respectively within the said pumping-barrels and respectively provided with upwardly-opening lift-valves; and a couple of vertically-swinging levers each provided with a stationary fulcrum or pivotal point, and having their opposite ends respectively connected with a barrel of one pumping set and a plunger-rod of the other pumping set, substantially as and for the purpose described. 25 30 35
